UNITED STATES PATENT OFFICE.

MARION S. MACCARTHY, OF DENVER, COLORADO.

SEPARATOR.

1,364,945.

Specification of Letters Patent. Patented Jan. 11, 1921.

Application filed January 12, 1918. Serial No. 211,525.

To all whom it may concern:

Be it known that I, MARION S. MACCARTHY, a citizen of the United States, residing at Denver, in the county of Denver and State of Colorado, have invented certain new and useful Improvements in Separators, of which the following is a specification.

This invention relates to apparatus for 10 the separation of comminuted metalliferous ores and other finely-divided materials, by the process described in my application for patent, Serial Number, 211524 filed synchronously with the present application.

15 It is the primary object of this invention to provide a combination of co-operative devices by which the separation process may be continuously carried on and by which a clean separation of refined concentrates from 20 the extraneous matter with which they were associated, is readily effected.

The process for the practice of which the present apparatus is particularly designed, consists briefly in feeding finely divided ore 25 or other material onto an upwardly moving inclined and preferably incurved surface from which the adherent matter is removed beyond a determinate elevation.

Advantage is taken of the difference in 30 the tendency of the ore particles to adhere to the surface, it having been observed that in certain ores the valuable particles are found to exist in the form of thin flat flakes which adhere to an inclined surface with 35 which they come in contact by friction or static attraction, while the particles of non-metalliferous matter are more rounded and of greater bulk and therefore have a natural tendency to move downwardly along the 40 same.

By imparting an upward movement to the inclined surface, the adhering concentrates are carried to an elevated point of discharge 45 separate from that at which the downwardly moving gangue is delivered, and by incurving the surface longitudinally the process of separation is expedited and promoted.

The process is particularly adapted for 50 recovering molybdenite from molybdeniferous ores, it having been observed that the molybdenite crystals appear practically invariably in the form of flakes, while the other constituents of the ore are thicker in proportion to their other dimensions and of 55 more rounded form.

In the present invention the upwardly moving inclined surface is provided by the interior of a rotating cylinder; the material is continuously fed into the cylinder at one of its ends, the gangue is discharged at 60 its opposite end and the concentrates are mechanically removed from the upwardly moving side of the surface at a determinate variable elevation.

Means are provided to automatically sort 65 the middlings from the gangue in material discharged through the end of the cylinder, and the cylinder is mounted so that it may be longitudinally tilted to any desired degree within determinate limits. 70

With the above objects in view, my invention in its preferred form, consists in the constructions and arrangement of parts shown in the accompanying drawings in the several views of which like reference characters designate corresponding parts and in which—

Figure 1 is a longitudinal vertical section through the apparatus,

Fig. 2, a transverse section on the line 80 2—2, Fig. 1,

Fig. 3, a transverse section along the line 3—3, Fig. 1,

Fig. 4, a transverse section taken on the line 4—4, Fig. 1, 85

Fig. 5, a transverse section along the line 5—5, Fig. 1, and

Fig. 6, a fragmentary section taken along the line 6—6, Fig. 1.

Referring more specifically to the drawings, the reference character 2 designates an open-ended cylinder which is mounted for rotation about a substantially horizontal axis upon four sets of flanged wheels 3. 90

The cylinder has to this end two circumferential tires 4 which bear upon the treads of the wheels at opposite sides of the vertical plane passing through the axis of the cylinder, and the cylinder has furthermore a planed circumferential pulley-face 5 for 100 the application of a belt 6 by which in the operation of the apparatus, it is rotated in the direction of the arrow 7 in Fig. 2.

The sets of wheels upon which the cylinder is supported are rotatably mounted on 105 chairs 8 which rest upon a suitable foundation structure 9.

The wheels of each set are rotatably mounted at the upper end of an arm 10 which at its opposite end is pivotally con- 11

nected with the respective chair to permit of an adjustment of the wheels in case of wear or faulty alinement of the parts.

The chairs of the wheel-sets are also adjustable to vary the distance between them and thereby regulate the position of the axis of rotation of the cylinder with relation to the horizontal.

The adjustment of the chairs may be effected by any convenient means such as the screws 12 shown in the drawings which are supported in threaded lugs 13 fastened to the foundation structure, and which have a swivel connection with the respective chairs.

15 The cylinder 2 has a lining 14 made of wood or other suitable wear-resisting material and its feed-end has an inwardly projecting flange 15 which defines a central feed-opening 16.

20 The pulverized ore is fed into this opening through the instrumentality of a feed-screw 17 which is mounted on a shaft 18 extending in the axis of the cylinder. The outer end of the screw extends within a stationary feed-box 19 provided with a hopper 20 into which the material to be treated is fed through a superposed chute 21.

25 The chute delivers the material to one side of the feed-screw as shown in Fig. 5 of the drawings, and by changing the position of the chute to increase or decrease its distance from the screw, or its height above the same, the angle of repose of the material deposited in the feed-box may be varied at will 30 to regulate the rate at which it is carried into the cylinder.

35 The adjustment of the chute may be effected by any suitable mechanism such as that shown in Fig. 1 of the drawings in which the reference numeral 60 designates a rotary pinion which meshes with a rack 61 on the chute which is mounted for up and downward movement between guides 62.

40 The shaft 18 carries in addition to the feed-screw, a longer screw 22 which extends from a point adjacent the feed-end of the cylinder to a point of delivery beyond the opposite end thereof for the discharge of the concentrates as will hereinafter be more 45 fully explained.

45 The two screws are inclosed by a tubular conduit 23 which is rotatably mounted in boxes 24 supported upon I-beams 25 beyond the ends of the cylinder. The end of the 50 conduit 23 beyond the feed-end of the cylinder is connected with an opening of the feed-box 19 and the joint between the conduit and the opening is sealed against the escape of air by means of a stuffing box 26.

55 The conduit connects at its opposite end with a receiving chamber 27 which communicates with a downwardly extending delivery chute 28. The joint between the conduit and the opening of the receiving 60 chamber is likewise made air-tight by a

stuffing-box 29 and the chamber is by means of a pipe 30 connected with an exhaust pump of suitable construction for the removal of concentrates from the interior surface of the cylinder as will hereinafter 70 be more fully described.

A screen 31 placed between the chamber 27 and the pipe 30 which connects it with the suction opening of the exhaust pump, 75 prevents the concentrates from being carried into the pump, and a rotary valve 32 fitted in a housing 33 placed between the chamber and the delivery chute 28 closes the outlet of the chamber against communication with the atmosphere.

80 The valve 32 consists of a cylindrical body having equidistant peripheral pockets 34 which register intermittently with the outlet of the chamber and the upper end of the delivery chute and it is in the operation of the apparatus continuously rotated by its connection with the shaft 18 through the intermediary of a sprocket-chain 35.

85 A disk 36 on the rotary conduit 33 placed exteriorly of the feed-end of the cylinder, 90 closes the feed-opening 16 of the same around the conduit 23, by its lapping position with relation to the flange 15. The conduit also carries a spout 37 which extends downwardly inside the cylinder contiguous 95 to the flange 15 and in connection with an opening in the conduit through which the feed-screw discharges its load.

90 The spout has at its lower end a narrow port 38 through which the material is delivered in close proximity to the inner circumferential surface of the cylinder.

100 A partition 39 in the conduit separates its feed-portion from the compartment in which the delivery screw is contained, and a stuffing-box 40 on this partition prevents the escape of air around the shaft 18.

105 The delivery compartment of the conduit which houses the screw 22 has a narrow slot in connection with a radially extending nozzle 41 the mouth of which is spaced from the inner circumferential surface of the cylinder and extends along the entire length thereof.

110 A brush 42 which is fastened within the mouth of the nozzle is composed of sparse bristles which engage the surface of the cylinder for the purpose of dislodging the material adhering thereto.

115 In the operation of the machine the conduit 23 is held against rotation by a worm 43 which is mounted in bearings on the feed-box as best shown in Fig. 5, and which meshes with a correspondingly toothed wheel 44 on the conduit 23.

120 A hand-wheel 45 on the worm-shaft facilitates its rotation whenever it is desired to change the position of the nozzle and delivery spout within the cylinder by rotation of the conduit.

The gangue obtained in the process of separation is discharged through the delivery end of the conduit into a hopper 45 which is loosely suspended from the conduit 5 by means of a sleeve 46 at the upper end of a pair of convergent arms 47 to which it is attached.

The hopper is by means of a partition 48 divided into two compartments which 10 separately connect with spouts 49 placed beneath the lower end thereof and it has a limited adjustment by rotation around the conduit from which it is suspended to vary the position of the partition with relation to the 15 perpendicular passing through the axis of rotation of the cylinder.

A segmental cross-arm 50 on the suspension arms of the hopper coöperates with a clamp 51 on the adjacent I-beam 25 upon 20 which the conduit is supported, to fix the hopper in its adjusted positions.

In the operation of the apparatus, the cylinder revolves upon its rotary bearings in the direction of the arrow in Fig. 2, and 25 the shaft is rotated in the same direction by its connection with a conveniently located motive agent through the intervention of a belt applied to a pulley 52 at one of its ends.

The finely divided ore or other material to 30 be treated is continuously supplied to the feed-box through the hopper 20 and is fed into the cylinder by the rotary movement of the feed-screw, in quantities which are regulated by adjustment of the feed-chute 35 21 as hereinbefore explained.

The feed-screw carries the material from the feed-box into the spout 37 which delivers it in a thin stream in close proximity to the inner circumferential surface of the cylinder 40 adjacent the feed-end thereof and thereby compels it to spread evenly along the entire length of the said surface at the lower portion of the same.

By the rotary movement of the cylinder 45 the material is carried upwardly upon the upwardly moving side of its inner surface. During this upward movement the thin flaky particles of the finely divided material will adhere to the surface of the cylinder during a longer period than the less flaky or rounded particles of extraneous matter which roll downwardly at velocities which are in ratio to their different forms and sizes.

The material is in consequence stratified 55 against the upwardly moving side of the cylinder according to the nature of its different particles, the flaky particles being carried upwardly by frictional or static adherence to the surface beyond the middlings which remain in a lower position above the gangue which rolls downwardly to the bottom portion of the cylinder.

The middlings and the gangue are gradually conducted toward the delivery end of

the cylinder through which they are separately discharged into the compartments of the hopper 45, it being understood that by the adjustment of this hopper, as hereinbefore explained, the position of the dividing 70 wall between its compartments may be varied so as to effect a clean separation between the middlings and the gangue on the bottom of the cylinder.

The flaky particles which are carried farther upward by their adherence to the surface of the cylinder are mechanically dislodged therefrom by the brush and the suction at the mouth of the nozzle 41. Immediately upon being detached from the cylindrical surface, the particles are drawn through the nozzle into the conduit and onto the delivery screw which carries them into the chamber 27 from which they are discharged past the valve 32, into the 85 chute 28.

By this treatment of materials such as molybdenite ores which are characterized by the flaky form of their valuable mineral constituents, a clean separation of the refined concentrates from the gangue is effected with an expenditure of but little mechanical energy and at a rate which is limited only by the amount of a continuous feed and the carrying capacity of the interior surface of the cylinder.

The adjustment of the conduit which carries the suction nozzle and the feed-delivery spout, determines the cleanliness of the refined product, and the adjustment of the 100 hopper at the discharge-end of the cylinder controls the line of separation between the middlings and the gangue.

It will be seen that the adherence of the flaky ore-particles to the upwardly moving 105 side of the annular surface of the cylinder is aided by centrifugal force and may or may not be aided by the static electricity generated by the friction between the cylindrical surface, the material moving downwardly thereon and the brush by which the adhering concentrates are removed, and that by tilting the cylinder by adjustment of the sets of wheels upon which it is supported, the gangue-discharge may be regulated in 110 accordance with the nature of the material under treatment.

While I have shown and described the different parts of which my improved separating mechanism is composed, in the best 120 and simplest form at present known to me, I desire it understood that variations in the construction and arrangement of the parts as may suggest themselves from time to time may be availed of within the spirit of my 125 invention as defined in the following claims.

I claim—

1. A separating apparatus comprising a rotary hollow cylinder, a feed-box discharging onto the interior circumferential sur- 130

- face thereof, a feed-screw carrying material in said box to the point of discharge, a chute feeding material into the box and having an adjustment to regulate the discharge into the cylinder by varying the angle of repose of material in the box, and means for removing from said surface, matter carried upwardly by frictional adherence.
10. 2. A separating apparatus comprising a rotary hollow cylinder open at one end for the admission of material and open at its opposite end for the discharge of gangue, means for removing from the interior circumferential surface of the cylinder, matter carried upwardly by frictional adherence, and means for dividing material discharged at the gangue-discharge end of the cylinder, according to the positions of its different constituents upon the upwardly moving side of said surface.
15. 3. A separating apparatus comprising a rotary hollow cylinder open at one end for the admission of material and open at its opposite end for the discharge of gangue, means for removing from the interior circumferential surface of the cylinder, matter carried upwardly by frictional adherence, and adjustable means for dividing material 20 discharged at the gangue-discharge end of the cylinder, according to the positions of its different constituents upon the upwardly moving side of said surface.
25. 4. A separating apparatus comprising a rotary hollow cylinder open at one end for the admission of material and open at its opposite end for the discharge of gangue, means for removing from the interior circumferential surface of the cylinder, matter 30 carried upwardly by frictional adherence, and a hopper having a dividing wall to separate material discharged at the gangue-discharge end of the cylinder according to the positions of its different constituents upon 35 the upwardly moving side of said surface, said hopper being adjustable to vary the elevation of the upper end of its dividing wall.
40. 5. A separating apparatus comprising in combination a rotary hollow cylinder, a conduit divided into a feed-compartment discharging onto the interior surface of the cylinder and a delivery compartment discharging outside the same, a rotary shaft extending through the conduit, feed-screws on

said shaft within the compartments of the 55 conduit, and a nozzle on the delivery-compartment of the conduit having an orifice extending lengthwise of and adjacent to the interior surface of the cylinder to remove therefrom matter carried upwardly by frictional adherence.

6. A separating apparatus comprising in combination a rotary hollow cylinder, a conduit divided into a feed-compartment discharging onto the interior surface of the 65 cylinder and a delivery-compartment discharging outside the same, a source of suction in connection with the delivery-compartment of the conduit, and a nozzle on the delivery-compartment of the conduit 70 having an orifice extending lengthwise of and adjacent to the interior surface of the cylinder to remove therefrom matter carried upwardly by frictional adherence.

7. A separating apparatus comprising in 75 combination a rotary hollow cylinder, a conduit divided into a feed-compartment discharging onto the interior surface of the cylinder and a delivery compartment discharging outside the same, and a nozzle on the delivery-compartment of the conduit 80 having an orifice extending lengthwise of and adjacent to the interior surface of the cylinder to remove therefrom matter carried upwardly by frictional adherence, said 85 conduit being adjustable by rotation to vary the position of the nozzle within the cylinder.

8. A separating apparatus comprising in combination, a rotary hollow cylinder of 90 even and imperforate inner surface, having an opening for feeding material onto said surface, a conduit having a suction-opening and a discharge-opening, a nozzle on the conduit having a mouth extending lengthwise of and in spaced relation to the surface above the horizontal plane of the axis of 95 rotation of the cylinder, and a valve constantly closing the discharge opening of the conduit from the atmosphere and operating 100 to effect the removal of material passing through the same.

In testimony whereof I have affixed my signature in presence of two witnesses.

MARION S. MACCARTHY.
